UNITED STATES PATENT OFFICE.

FELICJA GRINOCH, OF NEW YORK, N. Y., ASSIGNOR TO J. & M. COHN, OF NEW YORK,
N. Y., A FIRM.

DESIGN FOR A SHIRT-WAIST.

49,116.

Specification for Design.

Patented May 30, 1916.

Application filed March 9, 1916. Serial No. 83,208. Term of patent 3½ years.

To all whom it may concern:

Be it known that I, FELICJA GRINOCH, a citizen of France, residing in the borough of Manhattan, city, county, and State of New York, have invented a new, original, and ornamental Design for Shirt-Waists, of which the following is a specification, reference being had to the accompanying drawing, forming a part thereof.

Copies of this patent may be obtained for five cents each, by addressing the "Commissioner of Patents, Washington, D. C."

I claim:

The ornamental design for a shirtwaist, as shown.

In testimony whereof I have signed this specification in the presence of two subscribing witnesses.

FELICJA GRINOCH.

Witnesses:

JACOB THOMAS,
P. GILBERG.
